UNITED STATES PATENT OFFICE.

GEORGE M. BENNETT, OF BURLINGTON, IOWA.

FOLDING IRONING BOARD AND STAND.

SPECIFICATION forming part of Letters Patent No. 372,356, dated November 1, 1887.

Application filed November 23, 1886. Serial No. 219,699. (No model.)

To all whom it may concern:

Be it known that I, GEORGE M. BENNETT, a citizen of the United States, residing at Burlington, in Des Moines county, State of Iowa, have invented a new and useful Improvement in Folding Ironing Boards and Stands, of which the following is a specification.

My invention relates to improvements in folding ironing boards and stands, in which a common ironing-board operates in conjunction with a folding stand for said board to rest on; and the object of my invention is to provide a device of this character that will be simple in construction and effective in operation. I attain these objects by the mechanism illustrated in the accompanying drawings and pointed out in the claim.

In the accompanying drawings, Figure 1 shows a view of my invention when unfolded. Fig. 2 is a view of my invention when folded.

Similar letters refer to similar parts throughout the several views.

In the drawings, A represents the leaf or top of my ironing-board, and has near its broader end the ears a and a'. Through ears a and a' passes the bar b.

B and B' are two legs connected by cross-piece c. These legs B and B' are pivoted upon bar b close to the ears a and a'.

C and C' represent two other legs, which are connected by a cross-piece, d. These legs are also pivoted upon bar b, but inside of legs B and B'. The legs C and C' in their lower ends are connected by bar f. Inside of legs C and C' there are pivoted upon bar f another pair of legs, (designated by D and D'), which latter legs are in their other end connected by bar g. Upon bar g, between legs D and D', there are pivoted a fourth pair of legs, (designated by E and E'). The legs D and D' are connected by the cross-piece k, and the legs E and E' are connected by the cross-piece l. The

cross-pieces c, d, k, and l are connected by a flexible belt, x, made of any suitable material, in such a manner that if the belt x is stretched 45 the different sets of legs will assume the position as illustrated in Fig. 1 of the drawings.

For the purpose of giving additional strength to the support the legs E and E' are connected by an additional cross-piece, o.

The operation of my invention is as follows: When belt x is stretched, my invention assumes the position as illustrated in Fig. 1 of the drawings, and in this position is ready for use. If, now, my mechanism is to be folded 55 and put aside, I slightly raise the leaf A in its smaller end. Next I bring legs E and E' up to and within legs D and D'. This being done, I push legs D and D' up to and within legs C and C'. Now I fold legs C and C' up 60 to the leaf A, and lastly I fold legs B and B' up to the leaf A and over the legs already folded, as described. Thus it will be seen that in the order described the different sets of legs will fold within each other and take up very 65 little space. My whole ironing board and stand is thus folded into a comparatively small space and is now ready to be put aside. The unfolding is just as simple as the folding.

What I claim as my invention, and desire to 70 secure by Letters Patent, is—

A folding ironing board and stand comprising the leaf A, the ears a and a', the bar b, the legs B and B', the cross-piece c, the legs C and C', the cross-piece d, the bar f, the legs D and D', the bar g, the cross-piece k, the legs E and E', the cross-pieces l and o, and the belt x, substantially as and for the purpose herein described.

GEORGE M. BENNETT.
